UNITED STATES PATENT OFFICE.

THOMAS PRATT, OF VALPARAISO, INDIANA, ASSIGNOR OF ONE-HALF TO
WILLIAM J. LIGHTCAP, OF SAME PLACE.

CARPET-STRETCHER.

SPECIFICATION forming part of Letters Patent No. 367,320, dated July 26, 1887.

Application filed February 5, 1887. Serial No. 226,724. (No model.)

To all whom it may concern:

Be it known that I, THOMAS PRATT, a citizen of the United States, residing at Valparaiso, in the county of Porter and State of Indiana, have invented a new and useful Machine for Stretching Carpets, (commonly called a "Carpet-Stretcher;") and I do hereby declare that the following is a full, clear, and exact description of the construction and operation of the same, reference being had to the annexed drawing, making a part of this specification.

A is the head, made of wood—size, six inches by fourteen inches—holding the brads or teeth L L, which fasten into the carpet. B B is a hinge connecting head A with lever D. C C are braces. H and K are strips containing holes 1 1 1, &c., providing for extending and enlarging the machine to fit different sized rooms.

The machine is operated as follows: The head A, containing teeth L L, is placed upon the carpet three or four inches from the edge, leaving distance or space enough to tack easily. The strip K lies on the carpet, the end of which, M, rests against the base-board on the side of the room opposite to place where carpet is to be tacked. By pushing down on lever D, either above or below bolt E, the head A moves, thus bringing carpet to the required place.

When carpet is stretched to the required place, if only one person is at work, the machine may be held in *statu quo* until carpet is tacked by

fastening hook E in screw-eyes g g, &c. The machine is adjusted to rooms of different sizes by changing bolts E E to different holes 1 1 in strips H and K. The strips D, H, and K are eight feet long in ordinary-sized machines.

The advantages which I claim for my stretchers are, first, there is no danger of tearing carpets, there being teeth enough to prevent such; second, the machine can be worked easily by a person in a standing position; third, the machine stretches the carpet the full length or width of the room.

What I claim as my invention, and desire to secure by Letters Patent, is—

In a carpet-stretcher, the combination of the head A, provided on its under side with a series of teeth, said head being hinged to the end of a lever, D, by a central hinge, B, and braces C C, the lever D provided at the end opposite the head with a hook, F, the extension-bar H, provided with a series of longitudinal perforations and with a series of staples with which the hook F may engage, and a perforated bar, K, the bars and lever being pivotally and adjustably connected to each other, whereby the carpet-stretcher may be adjusted to rooms of different widths and held in an extended position, the parts being organized substantially as shown.

THOMAS PRATT.
